Primary Examiner — Kelley A Donnelly*(74) Attorney, Agent, or Firm* — Vierra Magen Marcus LLP(57) **CLAIM**

The ornamental design for a portion of a retail display, as shown and described.

DESCRIPTION

FIG. 1 is a front perspective view of a portion of retail display.

FIG. 2 is a front elevation view of the portion of the retail display.

FIG. 3 is a right side view of the portion of the retail display. A left side view of the portion of the retail display is a mirror image of FIG. 4; and,

FIG. 4 is a top view of the portion of the retail display. In the drawings, the dot-dash broken lines represent the boundary between claimed and unclaimed subject matter. In the drawings, the dash-dash broken lines represent unclaimed subject matter.

1 Claim, 4 Drawing Sheets(56)
